UNITED STATES PATENT OFFICE.

HENRY RUPPEL, OF CLEVELAND, OHIO, ASSIGNOR TO AMERICAN STOVE COMPANY,
OF ST. LOUIS, MISSOURI, A CORPORATION OF NEW JERSEY.

LIGHTING DEVICE FOR GAS-STOVES.

1,125,726.

Specification of Letters Patent. Patented Jan. 19, 1915.

Application filed May 4, 1914. Serial No. 836,288.

To all whom it may concern:

Be it known that I, HENRY RUPPEL, a citizen of the United States, residing at Cleveland, in the county of Cuyahoga and 5 State of Ohio, have invented certain new and useful Improvements in Lighting Devices for Gas-Stoves, of which the following is a specification, reference being had therein to the accompanying drawing.

10 My invention relates to improvements in lighting devices for gas stoves.

The object of my invention is to provide a lighting attachment in which any of the 15 four burners of the gas stove can be lighted from a central simmering burner, which is preferably kept burning with a small flame or, if desired, the simmering burner can be dispensed with and the flame or gas can be conveyed across from one burner to the 20 other to ignite all four of the burners, as will be hereinafter more fully described.

Another object of my invention is to provide a lighter of this character which is formed as an integral part of the top grating and which can be readily removed and cleaned when desired and having certain 25 details of structure.

A still further object of my invention is to provide a simple, cheap and more effective lighter of this character in which the flame is more effectively conveyed across 30 from one burner to the other and in which the said lighter does not have to have an independent gas supply.

35 In the accompanying drawings Figure 1 is a top plan view of an improved four burner stove showing my invention applied thereto. Fig. 2 is a bottom plan view looking upwardly from above the burners. Fig. 40 3 is an enlarged vertical sectional view on the line 3—3 of Fig. 1. Fig. 4 is a vertical sectional view taken on the line 4—4 of Fig. 1, showing the specific arrangement of the 45 simmering burner. Fig. 5 is an enlarged top plan view of the simmering burner. Fig. 6 is an enlarged vertical sectional view taken 50 on the line 6—6 of Fig. 1, showing the burner supporting means. Fig. 7 is an enlarged perspective view of the burner supporting means removed from the frame. Fig. 8 is a top plan view similar to Fig. 1, showing a modified form of lighter for conveying the flame and gas directly across 55 from one burner to another. Fig. 9 is a top

plan view of a stove showing a solid top in 55 which the gas conveying channels are formed. Fig. 10 is a vertical broken sectional view showing the channel in full lines. Fig. 11 is a vertical transverse sectional view taken on the line 11—11 Fig. 10. 60

Referring now to the drawings, 1 represents a portion of an improved range which is provided at one side with the oven 2, and the other side with a shelf 3, all of which is of the well-known type and needs no further description, as my improved lighter is adapted to be applied to the ordinary stove or range without any modification. The portion 1 of the stove is provided with the usual burners four in number and designated by 4, 5, 6 and 7, arranged as shown in Fig. 1 of the drawing and having above the same the usual grating 8. This grating, as shown, is formed in two sections 9 and 10 having their inner ends abutting, as clearly 70 shown in Fig. 2 of the drawings. At the forward end of the stove 1, is the gas-supply pipe 11, having the four gas-supply valves connected thereto and supplying gas to the pipes 12, 13, 14 and 15 leading to the four 80 burners 4, 5, 6 and 7. These pipes are removably connected to the valves in the usual manner and which is well understood by those skilled in the art and needs no further 85 description.

Extending transversely across the stove adjacent the forward end is a bar 16, which is provided with a hooked end 17, adapted to hook into the opening 18 in the casting 19 cast with the stove 1, and whereby the 90 said bars are removably supported. The bar 16, adjacent its ends, is depressed, as indicated at 20 to support the two burner-pipes 12 and 15 leading to the two rear burners 4 and 5. Said bar adjacent the depressed portions is provided with openings 21 adapted to receive lugs carried by the lower ends of the burners 6 and 7, whereby the burners are supported by the bars against lateral movement. The stove 1, adjacent the rear end is provided with a bar 22, which is of a straight form and supported in the same manner as the bar 16. The said bar 22 is provided with openings 100 corresponding with the openings 21 in the bar 16 to receive the lugs carried by the two rear burners 4 and 5, whereby they are supported against lateral movement. 105

The gas-supply pipe 11 is provided with a central valve 23, which supplies gas to the simmering burner tube 24, and which leads inwardly across the bar 16 and provided 3 with a lug 25 passing through an opening 26 in the bar 16, whereby the said simmering burner is readily supported against lateral movement. The outer end of the tube 24 is turned upwardly at 27 and provided 10 with a series of small openings 28 through which the gas passes and is burned as is well understood. The upper flat end of the simmering burner is provided with four lugs 29, 30, 31 and 32, which have their edges 15 beveled, as indicated at 33, upon which is adapted to rest the lighting device, as will be hereinafter more fully described. Between the lugs 29, 30, 31 and 32 the upper face of the simmering burner is provided 20 with grooves 34 which allow the passage of gas across the upper end thereof, the purpose of which will be later described.

The gratings 9 and 10, as shown and described heretofore, are made in two sections 25 and have their inner ends abutting and provided with circular portions 35 at their abutting corners. Formed integral with the grating and extending a slight distance below the lower edge are four radially extending arms 36, 37, 38 and 39, which extend 30 adjacent the burners 4, 5, 6 and 7. These members, as shown, form a part of the grating and have in their lower faces V-shaped grooves 40, the inner ends of which communicate with each other when the two gratings are placed together to form the top of the stove. The outer ends of the members 36, 37, 38 and 39 are enlarged and turned downwardly, as indicated at 41, directly 35 above the outer end of the burners. This is true in respect to the burners 4, 5, and 6, but the burner 7 being of a greater length, the member 38 extends in about midway the length of the burner-arms of said burner. This downwardly turned portion 40, extending over and surrounding the end of the burner, allows the gas passing from the openings 42 of the burner to pass upwardly within the V-shaped grooves 40 in the lower faces of the members 36, 37, 38 45 and 39, which allows the gas and flame to travel in the said grooves, as will be herein-after more fully described.

The simmering burner, as heretofore described, is supported in a position directly below the junction of the four members 36, 37, 38 and 39, but owing to the grooves 34 between the lugs 29, 30, 31 and 32 the gas or flame is adapted to travel across above the 50 simmering burner and whereby my improved lighter can be used with or without the simmering burner. The lower edges of the members 36, 37, 38 and 39 are beveled, as indicated at 43 and which rest upon the 55 beveled faces 33 of the lugs 29, 30, 31 and

32, and whereby the grating is supported at the center by the simmering burner and yet allows of the free unobstructed passage of gas or flame across the top of the simmering burner.

In the modification shown in Fig. 8 of the drawings, the two sections of the grating 9 and 10 are arranged substantially like that shown in Fig. 1, excepting that they are provided with the lighting members 44, 45, 46, 47, 48, 49, 50 and 51. The members 44 and 45 form a part of the grating and have their inner ends abutting and provided with V-shaped grooves in their lower ends and arranged exactly the same as is the member 36 described as the preferred form and have their outer ends turned downwardly, as indicated at 41, in Fig. 3 of the drawing and the two members forming a continuous passage when the two grating sections 9 and 10 are placed together to convey the gas or flame across from the burner 4 to the burner 5, or vice versa. The remaining members 46, 47, 48, 49, 50 and 51 are arranged in pairs so as to convey the flame or gas across from 80 one burner to another. By this structure, shown in modification, the simmering burner is dispensed with but in order to light the stove one of the burners must be lighted by hand. An example of the operation is herein given. The burner 6 being lighted and it being desirous to light the burner 4, the gas is turned on to the said burner 4 and through the two members 50 and 51, the flame travels from the burner 6 100 inwardly in the V-shaped groove in the member 50 and the gas travels inwardly in the V-shaped groove 51 and they meet and the flame travels back through the member 51 to the burner and ignites the same. The 105 flame can thus be conveyed from the burner 4 to the burner 5 and from the burner 6 to the burner 7, or from any one of the burners to all of the burners, as will be readily understood.

In the preferred form, shown in Fig. 1 of the drawings, the simmering burner is first lighted and preferably kept lighted so that when it is desired to light any one of the burners, the gas is turned on to said burner. When the simmering burner is lighted, and should it be desired to light the burner 4, the gas is turned on thereto and passes out through the openings 42 into the V-shaped groove 40 in the downwardly turned end of 115 the member 36 and travels inwardly until it meets the flame of the simmering burner when it is ignited and the flame travels backward to the burner and ignites the gas as it passes from the openings 42. The gas from 120 one of the arms of the burner ignites the gas in the other arms of the burner, as is understood, as the structure of the burner is of the ordinary well-known form.

In gas stoves in which natural gas is used, 125

it is necessary to use a solid top as shown in Figs. 9 to 11, inclusive instead of the grating used in the ordinary stove. The solid top 52 is formed in two sections 53 and 54, 5 which are provided with openings 55 covered by the usual lids 56, which may be in two parts, as shown, or could be in a single piece all of which forms no part of this invention. The abutting edges of the sections 10 53 and 54, are provided with oppositely arranged semicircular openings 57 and 58, which form a circular opening just above the pilot light and is closed by a lid, not shown. The under sides of the sections 53 15 and 54 are provided with channels 59 which are formed by the two downwardly extending flanges 60 and 61, formed or cast integral with the sections. These channels extend radially from the center opening or 20 pilot simmering burner outwardly to the openings 55 and have the extensions 62, which are adapted to extend over the arms of the burners 63, the same as that shown in the form in which the grating is used. 25 The inner ends of the channels meet at a point directly below the center of the center opening and communicate with each other whereby the gas can be conveyed across in the channel from one burner to another and 30 ignited and the flame likewise travels across for igniting the different burners. When the pilot or simmering burner is used the flame therefrom ignites the gas in the channels, whereby any one or all of the burners 35 can be ignited therefrom.

In the use of the word top in the claims, applicant means either a solid top or a grating as both are used to support the cooking utensils, and applicant is wished to be understood that the term top be broad enough to cover either of the structures herein shown.

Having thus described my invention what I claim and desire to secure by Letters Patent is:

1. The combination in a gas stove, of a series of burners carried thereby, the top of the stove above the burners having grooves in its lower face and adapted to convey the 50 flames back and forth between the burners.

2. The combination in a gas stove, of a series of burners, a simmering burner located between the burners, the top of the stove having radially arranged passages in 55 its lower face intersecting above the simmering burner and extending outwardly over the ends of the main burners and adapted to convey the flames and gas back and forth from the simmering burner to the main 60 burner or back and forth between the main burners.

3. The combination in a gas stove, of a series of burners, the top of the stove having means for conveying the flames and gas 65 back and forth from one burner to another.

4. The combination in a gas stove, of a series of burners, the top of the stove having means formed integral therewith for conveying the flames and gas back and forth from one burner to another. 70

5. The combination in a gas stove, of a series of burners, radially arranged arms carried by the top of the stove and having their inner ends intersecting, and a simmering burner below the intersecting ends of the 75 arms, said arms adapted to convey the gas and flames back and forth between the main burners and the simmering burner.

6. The combination in a gas stove, of a series of burners, radially arranged arms 80 carried by the top of the stove and having their inner ends intersecting and having grooves in their lower face adapted to convey the flames and gas back and forth from one burner to another. 85

7. The combination in a gas stove, of a series of burners, the top of the stove formed in two sections, said sections having arms provided with grooves in their lower faces and arranged to communicate with each 90 other for forming means for conveying the flame and gas back and forth between the burners.

8. The combination in a gas stove, of a series of burners, a top formed in two sections above the burners, radially extending arms carried by each section and extending adjacent the burners and having grooves in their lower faces, and the said grooves in one of the sections communicating with one 100 of the grooves in the other section and adapted to convey the flame and gas back and forth between the burners. 95

9. The combination in a gas stove, of a series of burners, and a simmering burner, 105 the top of the stove having grooves intersecting above the simmering burner, said grooves having their extreme outer ends turned downwardly over the main burners, and adapted to convey the flame and gas 110 back and forth between the simmering burner and the main burner.

10. The combination in a gas stove, of a series of main burners and a simmering burner, the top of the stove having outwardly extending arms extending from the simmering burner to the main burner and having grooves in their lower faces adapted to convey the flame and gas back and forth between the simmering burner and the main 115 burner. 120

11. The combination in a gas stove, of a series of main burners, a simmering burner between the main burners, the top of the stove having arms formed integral therewith and extending from the simmering burner to the main burner and having grooves in their lower faces adapted to convey the flame and gas back and forth between the simmering burner and main burn- 125 130

ers or back and forth between the main burners, substantially as shown and described.

12. The combination in a gas stove, of a series of main burners and a simmering burner between the main burners, the top of the stove formed in two sections, arms formed integral with the sections and having their inner ends intersecting above the simmering burner and their outer ends above the main burner, said arms having grooves in their lower faces adapted to convey the flame and gas back and forth between the main burners and the simmering burner.

13. A gas stove of the character described having a main gas-supply at its front end, two horizontal removable bars extending across the stove below its upper end, the forward bar having depressed portions adjacent its ends and openings between the depressed portions, the rear bar having openings, burner tubes connected to the main gas supply adjacent each end of the stove and extending inwardly and resting upon the depressed portion of the forward bar and having lugs passing through said openings in the rear bar, and burners carried by the inner ends of the said tubes, a second series of burner tubes connected to the main gas supply and extending inwardly and having lugs passing through said openings in the forward bar on the inside of the depressed portion.

14. A gas stove of the character described having a main gas supply at its front end, two horizontal removable bars extending across the stove below its upper end, the rear bar having openings, the forward bar having depressed portions adjacent its ends, burner tubes connected to the main gas supply adjacent each end of the stove and extending inwardly and resting upon the depressed portions of the forward bar and having lugs passing through said openings in the rear bar, burners carried by the inner ends of the said tubes, said forward bar having openings intermediate the depressed

portions, a second series of burner tubes connected to the main gas supply and extending inwardly and having lugs passing through said openings in the forward bar, a tube connected to the main gas-supply and extending across the forward bar and having a lug passing through an opening therein, and a simmering burner on the inner end of said last named tube and located between the main burners.

15. The combination in a gas stove, of a series of main burners and a simmering burner located between the main burners and having a series of openings around its periphery, upwardly extending spaced lugs between the said openings and having beveled edges, radially extending arms carried by the top of the stove and formed integral therewith and extending adjacent the burners and having their inner ends intersecting, said arms having grooves in their lower faces and provided with beveled edges at their inner ends adapted to rest upon the beveled edges of the lugs whereby the grooves of the arms intersect and have an unobstructed passage above the simmering burner.

16. The combination with a gas stove, of a series of burners, the top of the stove having channels formed on the lower face and extending inwardly over the burners and adapted to convey the gas and flame back and forth between the burners.

17. The combination in a gas stove, of a series of main burners and a simmering burner located between the main burners, the lower face of the top having radially extending arms intersecting above the simmering burner and adapted to convey the flames and gas back and forth from the simmering burner to the main burners or back and forth between the main burners.

In testimony whereof I hereunto affix my signature in the presence of two witnesses.

HENRY RUPPEL.
